Fig. 5

Fig. 6

FIG. 1 is a front elevational view of a glove embodying my new design;

FIG. 2 is a rear elevational view thereof;

FIG. 3 is a cross sectional view taken on the line 3—3 of FIG. 1;

FIG. 4 is a front elevational view of another embodiment of the design shown in FIG. 1;

FIG. 5 is a rear elevational view thereof; and

FIG. 6 is a cross sectional view taken on the line 6—6 of FIG. 4.

This application is a continuation of application Ser. No. D-14,439 filed Nov. 13, 1968, and application Ser. No. D-17,600, filed June 9, 1969, both now abandoned.

I claim:

The ornamental design for a rubber glove, as shown and described.
